UNITED STATES PATENT OFFICE

LEONHARD HAAG, OF FRANKFORT-ON-THE-MAIN, GERMANY

ELECTRIC SWITCH

Application filed May 1, 1930. Serial No. 449,022.

This invention relates to excess current release devices so constructed that they can be used for the releasing of various kinds of apparatus and can be secured in position and exchanged in a simple manner.

An object of the invention is to provide a device of the character described in which a toothed wheel release mechanism normally locked by a fusible mass, of the smallest possible dimensions and heat consumption may be employed. Another object is to provide such a device with an electromagnetic release acting immediately on the occurrence of sudden violent surges such as short circuit currents and with means for adjusting the whole device to suit different operating conditions, a single adjustment being effective both as regards the ratchet wheel release mechanism and the electromagnetic release. A further object is to provide a readily adjustable device which acts indirectly through a mechanical energy store so that auxiliary contacts are avoided and so that a small compact device is enabled to release relatively large apparatus. A still further object of the invention is to provide a structure with simple regulating means in which the current at which the electromagnetic release act and that at which, for a given time lag, the thermal release acts are variable in common but in accordance with different and independent functions of the exciting current.

With these objects in view, my invention comprises the combinations described below and pointed out in the appended claims.

In the accompanying drawings

Figure 1 is an automatic switch furnished with two release devices constructed in accordance with the invention. Figure 2 is a section on an enlarged scale on the line II-II of Figure 1, seen in the direction of the arrows.

Figure 3 shows how the same release devices as shown in Figures 1 and 2, can be applied to other apparatus.

Figures 4 and 5 are two views at right angles to one another of the transformer with the armature for effecting release on the occurrence of heavy overloads and the adjusting armature.

Figures 6 and 7 are corresponding views showing the armatures in a second position and

Figures 8 and 9 are corresponding views showing the armatures in a third position.

The details not necessary for following the arrangement of the armatures have been omitted from Figures 4-9.

No detailed description of the switch shown in Figures 1 and 2 is given since it is not in itself part of the invention and is not necessary for comprehension thereof. The invention resides solely in the arrangement of the excess current release devices.

The release mechanism 4 comprising a toothed wheel normally locked by a fusible mass, is secured on the iron core 2 of a current transformer by means of a mounting member 3. The windings of the transformer, of which only one is visible in the drawings since the second is covered by the first, are mounted on the middle limb of the core 2. The primary winding of the transformer is traversed by the current in the circuit to be protected from overloads. The secondary winding is traversed by a current of small strength serving to heat the fusible mass of the release mechanism 4. Such release mechanisms are well known and a detailed description is therefore unnecessary. They consist of a toothed wheel which is held stationary by the fusible mass which is heated by an electric current. When a current of relatively small excess value but of relatively long duration flows, the mass softens or melts so that the wheel is released and can rotate under the influence of a force.

With the teeth of the wheel of the release mechanism 4 meshes a member 5 by means of a small tooth like projection. The member 5 can have several such projections and thus be in the form of a rack. It is pivotally or yieldably secured to a plate 6 and displaceable against spring pressure so that it can be moved out of engagement with the teeth of the wheel of the mechanism 4. Advantageously the member 5 as shown in the drawings consist of a spring blade. The plate 6 which serves as the release member is pivoted to a projection 7 on the core 2. Another projection 8 on the

core 2 serves for anchoring a helical spring 9 the other end of which is held by a nose 10 on the plate 6. The spring 9 tends to rotate the plate 6 but cannot do so as long as the member 5 is in mesh with the wheel 4 and the fusible mass unmelted. An armature 12 which serves to effect release on the occurrence of short circuits and like violent surges of current, is pivoted on a shaft 11 carried by the core and is under the influence of the magnetic field of the transformer. On the shaft 11 is also pivoted an adjusting armature 13 which serves for adjusting the magnetic resistance of the transformer core and thus for regulating the strength of the secondary current which heats the fusible mass. To the core is secured a scale plate 14 which serves to indicate the adjustment of the armature 13 and to which the latter can be clamped by a nut 16 on a screw working in a slot 15 on the plate. To the plate 14 is secured one end of a helical spring 17 the other end of which is secured to the armature 12 and tends to draw it away from the pole of the core 2 which attracts it. The laminations of the armatures 12 and 13 are arranged in staggered relationship and intermesh one group with the other.

In Figures 4 and 5 the adjusting armature 13 is entered as far as possible into the armature 12 so that the air gap 18 between them which increases the magnetic resistance is made as small as possible.

Figures 6 and 7 show a setting of the armature 13 in which the air gap 18 is larger and the ratio of transformation therefore smaller.

Figures 8 and 9 show the largest air gap 18 obtainable by adjusting the armature 13. By adjustment of the armature 13 not only is the magnetic resistance between itself and the armature 12 varied, but also that between itself and the adjacent limb of the core 2.

If a relatively small but nevertheless excessive current flows, the armature 12 will not be attracted with sufficient force to overcome the pull of the spring 17 and the armature will not move. On the other hand after the lapse of a certain time the fusible mass of the mechanism 4 will soften owing to the heating effect of the current and the wheel will be free to rotate. Accordingly the part 6 can turn under the influence of the spring 9. The rotation of the plate serves to release the locking device of the apparatus to which the releasing device is attached.

Upon a short circuit occurring damage might be done before the fusible mass of the mechanism 4 had softened sufficiently. In this case the release is effected by the armature 12 which is attracted by the magnetic force of the core sufficiently to overcome the force of the spring 17 and is immediately moved against the member 5 which stands in its path, and thus moves the member 5 out

of mesh with the wheel mechanism 4 so that the part 6 can rotate under the action of the spring 9 and release the locking device of the apparatus to which the device is attached.

The advantage of the invention lies in the simplicity of the mounting. A few simple hand operations suffice to add the device all ready for operation to a switch as shown in Figures 1 and 2. In the event of damage the release device can be immediately exchanged and the switch again made ready for use. Since the release device is a constructional unit it can be used in the most varied kinds of apparatus, as can be gathered from Figure 3 where it is shown mounted on an insulator 19 and provided with an operating rod 20 which conveys the releasing motion of the member 6 to the locking device of the apparatus in question.

What I claim is:—

1. In an indirect electric release device, the combination of a magnetic core, an exciting winding upon said core, a release member movably mounted on said core, spring means for actuating said release member anchored to said core, an armature pivoted to said core and under the influence of the magnetic field thereof, a secondary winding upon said core, a release mechanism actuated by small but protracted excess currents fed by said secondary winding and mounted on said core, a catch on said release member in the path of said armature and normally held by said release mechanism, an adjusting armature pivoted to said core for adjusting the ratio of transformation between said exciting winding and said secondary winding, a projection on said adjusting armature lying in the magnetic circuit of said first mentioned armature adapted to alter the reluctance thereof, a scale plate secured to said core, means for clamping said adjusting armature to said scale plate, and a spring connected between said scale plate and said first mentioned armature tending to draw said first mentioned armature away from said core.

2. In an indirect electric release device, the combination of an open circuit magnetic core, an exciting winding upon said core, a release member movably mounted on said core, spring means for actuating said release member anchored to said core, an armature pivoted to said core forming a partial closure of said open circuit, a secondary winding upon said core a release mechanism actuated by small but protracted excess currents fed by said secondary winding and mounted on said core, a catch on said release member in the path of said armature and normally held by said release mechanism, and an adjusting armature for regulating the ratio of transformation between said exciting winding and said secondary winding, a projection on said adjusting armature lying

in the magnetic circuit of said first mentioned armature adapted to alter the reluctance thereof.

3. In an indirect electric release device, the combination of a three limbed open circuit magnetic core, a release member movably mounted on said core, an exciting winding on the center limb of said core, a secondary winding on the center limb of said core, spring means for actuating said release member anchored to said core, an armature for effecting release on the occurrence of heavy overloads in said exciting winding and an adjusting armature both pivoted to the center limb of said core on a common shaft and extending in opposite directions towards the two outer limbs of said core respectively, said armatures also intermeshing in the neighborhood of said shaft, means for adjustably holding said adjusting armature, means urging said first mentioned armature away from the respective outer limb of said core, a release mechanism actuated by small but protracted excess currents fed by said secondary winding and mounted on said core, and a catch on said release member in the path of said first mentioned armature and normally held by said release mechanism.

4. In an indirect electric release device, the combination of an open circuit magnetic core, a release member pivoted to said core, an exciting winding upon said core, a secondary winding linked by the whole flux on said core, spring means for actuating said release member anchored to said core, an armature pivoted at one end to said core closing part of its open circuit, an adjusting armature extending between said core and said first mentioned armature, means for adjusting the gaps between the ends of said armatures and said core respectively, means urging said first mentioned armature to swing out of the magnetic circuit, a release mechanism actuated by small but protracted excess currents fed by said secondary winding and mounted on said core, and a catch on said release member in the path of said first mentioned armature and normally held by said release mechanism.

5. An indirect overload release device comprising a magnetic core, an exciting winding on said core, a secondary winding linked by the whole flux on said core, a toothed wheel release mechanism mounted on said core, a fusible mass normally locking said wheel mechanism and heated by the output of said secondary winding, an armature pivoted to said core and under the action of the magnetic field thereof, a movable release member carried by said core, a blade spring on said release member in the path of said armature and meshing with the wheel of said wheel mechanism, an adjusting armature pivoted to said core for adjusting the ratio of transformation between said exciting winding and

said secondary winding, a projection on said adjusting armature lying in the magnetic circuit of said first mentioned armature adapted to alter the reluctance thereof, a scale plate secured to said core, means for clamping said adjusting armature to said scale plate, and a spring connected between said scale plate and said first mentioned armature tending to draw said first mentioned armature away from said core.

6. An indirect overload release device comprising a magnetic core, an exciting winding on said core, a secondary winding linked by the whole flux on said core, a toothed wheel release mechanism mounted on said core, a fusible mass normally locking said wheel mechanism and heated by the output of said secondary winding, a movable release member carried by said core, a blade spring on said release member meshing with the wheel of said wheel mechanism, means on said core for disengaging said blade spring from said wheel on the occurrence of violent surges such as short circuit currents and a second armature pivoted to said core for adjusting the ratio of transformation between said exciting winding and said secondary winding, a projection on said adjusting armature lying in the magnetic circuit of said first mentioned armature adapted to alter the reluctance thereof.

7. An indirect overload release device comprising a magnetic core, an exciting winding upon said core, a secondary winding upon said core, a toothed wheel rotatably mounted on said core, a fusible mass normally locking said wheel and heated by the output of said secondary winding, a movable release member pivoted upon said core, spring means anchored to said core for actuating said release member, a pawl on said release member normally meshing with said wheel whereby said release member and spring means are held out of action, an armature pivoted to said core to complete the magnetic circuit thereof in such position as to disengage said pawl from said wheel when attracted by said core upon the flow of heavy overloads through said exciting winding, means opposing attraction of said armature, a second armature pivoted to said core for adjusting the ratio of transformation between said exciting winding and said secondary winding, and a projection on said second armature lying in the magnetic circuit of said first mentioned armature and adapted to alter the reluctance of said magnetic circuit.

8. An indirect overload release device comprising a magnetic core, an exciting winding upon said core, a secondary winding upon said core, a toothed wheel rotatably mounted on said core, a fusible mass normally locking said wheel and heated by the output of said secondary winding, a movable release member pivoted upon said core, spring means

- anchored to said core for actuating said release member, a blade spring on said release member, a pawl on said blade spring normally meshing with said wheel whereby said release member and said spring means are held out of action, an armature pivoted to said core to complete the magnetic circuit thereof in such position as to move said blade spring and thus disengage said pawl from said wheel when attracted by said core upon the flow of heavy overloads through said exciting winding, means opposing attraction of said armature, a second armature pivoted to said core for adjusting the ratio of transformation between said exciting winding and said secondary winding, and a projection on said second armature lying in the magnetic circuit of said first mentioned armature and adapted to alter the reluctance of said magnetic circuit.
- 20 In testimony whereof I have signed my name to this specification.
